US00D929173S

(12) **United States Design Patent** (10) **Patent No.:** **US D929,173 S**
(45) **Date of Patent:** **** Aug. 31, 2021**

(54) **FOOD PREPARATION DEVICE**

(71) Applicant: **SharkNinja Operating LLC**,
Needham, MA (US)

(72) Inventors: **Da Deng**, Newton, MA (US); **Dan Kestenbaum**, Brookline, MA (US)

(73) Assignee: **SharkNinja Operating LLC**,
Needham, MA (US)

(**) Term: **15 Years**

(21) Appl. No.: **29/771,433**

(22) Filed: **Feb. 23, 2021**

Related U.S. Application Data

(62) Division of application No. 29/733,272, filed on Apr. 30, 2020, which is a division of application No. (Continued)

(57) **CLAIM**

The ornamental design for a food preparation device, as shown and described.

DESCRIPTION

FIG. 1 is a perspective view of a food preparation device, showing our new design;

FIG. 2 is a front view of the embodiment shown in FIG. 1; FIG. 3 is a rear view of the embodiment shown in FIG. 1; FIG. 4 is a side view of the embodiment shown in FIG. 1; FIG. 5 is another side view of the embodiment shown in FIG. 1;

FIG. 6 is a top view of the embodiment shown in FIG. 1; and,

FIG. 7 is a bottom view of the embodiment shown in FIG. 1.

The broken lines in the figures are for environmental purposes only and form no part of the claimed design.

1 Claim, 7 Drawing Sheets
